TIERED PLANTER

Jay V. Zimmerman, 7754 Davis Drive,
Clayton, Mo. 63105

Continuation of design application Ser. No. 86,174, July 14, 1965, which is a continuation of design application Ser. No. 79,935, May 11, 1964. This application Dec. 23, 1965, Ser. No. 928

Term of patent 14 years

(Cl. D35—3)

FIG. 1

FIG. 3

FIG. 2

FIG. 4

FIGURE 1 is a top plan view of a tiered planter embodying my new design.

FIGURE 2 is a front elevational view thereof.

FIGURE 3 is a side elevational view thereof.

FIGURE 4 is a bottom plan view thereof.

Portions of the planter have been omitted in FIGS. 1 and 4 for ease of illustration.

The characteristic feature of my design resides in the specific arrangement of a plurality of vertically tiered sections which are nested within each other as best seen through the transparent walls of said sections in FIGS. 2 and 3 on the drawing.

This application is a continuation of design application Serial No. D86,174, filed July 14, 1965, which is a continuation of design application Serial No. D79,935, filed May 11, 1964, and now both abandoned.

I claim:

The ornamental design for a tiered planter, as shown and described.
